(12) **United States Design Patent** (10) Patent No.: **US D778,060 S**
Finkel et al. (45) Date of Patent: ** Feb. 7, 2017

(54) **TOOTHBRUSH WITH DENTAL FLOSS DISPENSER**

(71) Applicant: **FINKELFLOSS LTD.**, Herzelia (IL)

(72) Inventors: **Itzhak Finkel**, Herzelia (IL); **Elad Etingold**, Tel Mond (IL); **Arthur Visokowski**, Yavne (IL)

(73) Assignee: **FINKELFLOSS LTD.**, Herzelia (IL)

(**) Term: **14 Years**

(21) Appl. No.: **29/518,655**

(22) Filed: **Feb. 26, 2015**

(30) **Foreign Application Priority Data**

Aug. 26, 2014 (IL) 55965
